UNITED STATES PATENT OFFICE.

WILLIAM N. ROMANOFF, OF CHICAGO, ILLINOIS.

NECKTIE.

Application filed August 16, 1926. Serial No. 129,353.

This invention relates to neckties. It is a known fact that the necktie by being frequently tied and untied loses its shape and tears. Therefore the object of the present invention is to provide means for positioning the tie upon user's neck without necessity of tying and untying the same when it is desired to remove the tie from the neck.

Another object of the invention is the provision of simple and efficient means for attaching the tie to the user's neck.

With the above general objects in view and others that will appear as the nature of the invention is better understood, the same consists in the novel construction, combination and arrangement of parts herein-after more fully described, illustrated in the accompanying drawing and pointed out in the appended claims.

20 In the drawing forming a part of this application and in which like designating characters refer to corresponding parts throughout the several views,

Fig. 1 is a front elevational view of the tie;

Fig. 2 is the view of the untied tie;

Fig. 3 is a top view of the fastening means; and

Fig. 4 is the front view of the fastening means of the tie.

The tie shown on the drawing is one of the "four-in-hand" type comprising knot 10 and scarf 11, both formed by tying in regular way. Neckband 12 on a line substantially opposite from knot 10 is slit. The lower corners of the neckband at the slit are cutaway forming a substantially inverted V-shaped incision 13 for the purposes hereinafter stated.

40 One part of the neckband is provided with loop 14 and the opposite end of the other part of said neckband is provided with hook 15 for engaging said loop.

From the hereinabove description it will be apparent that the two portions of the neckband 12 are adapted to become joined by virtue of loop 14 and hook 15 which provide fastening means for said neckband upon the neck of the wearer.

50 The operation of the tie is as follows: Originally knot 10 is formed for more or less permanent use without untying or tying

the same. To place the tie upon wearer's neck loop 14 and hook 15 are disengaged and the two parts of the neckband 12 are placed around the wearer's collar and thereupon are attached by engaging hook 15 in loop 14. The V-shaped incision 13 will permit the rear collar button to project beyond the tie, and thus the neckband 12 will not interfere with the rear collar button.

To obtain best results from the tie hereinabove described it will be borne in mind that loop 14 and hook 15 are attached to the respective portions of the neckband at the upper edge thereof so that they may not interfere with the V-shaped incision 13.

While there is described herein a preferred embodiment of the present invention, it is nevertheless to be understood that minor changes may be made therein without departing from the spirit and scope of the invention as claimed.

What I claim as new is:

1. In a necktie, a sectional neckband for the tie, the ends of said sections adapted to be positioned adjacent, but not touching each other when the band is disposed about the neck of a wearer, a separable connection the elements of which are carried by the respective ends of the neckband for attaching the said ends together, the portions of said ends of the sections below the separable connection being cut away to form a notch for receiving the button of a collar, and said notch communicating with the space between the ends.

2. In a necktie, a two-part neckband for the tie, the ends of the parts adapted to be positioned adjacent to but not touching each other when the band is disposed about the neck of a wearer, a separable connection the elements of which are carried upon the upper portions of the respective ends of the parts for attaching said parts together, the lower portions of the said ends of the parts below the separable connection being cut away at an angle in opposite directions to form a substantially triangular notch for receiving the button of a collar, and said notch communicating with the space between the ends.

In testimony whereof I affix my signature.

WILLIAM N. ROMANOFF.
